UNITED STATES PATENT OFFICE.

JOHN C. MAXSON AND WILLIAM O. WALKER, OF CORNING, KANSAS.

TOOL.

1,255,546.

Specification of Letters Patent.

Patented Feb. 5, 1918.

Application filed February 28, 1916. Serial No. 80,967.

To all whom it may concern:

Be it known that we, JOHN C. MAXSON and WILLIAM O. WALKER, citizens of the United States, residing at Corning, in the 5 county of Nemaha, State of Kansas, have invented certain new and useful Improvements in Tools; and we do hereby declare the following to be a full, clear, and exact description of the invention, such as will enable 10 others skilled in the art to which it appertains to make and use the same.

This invention relates to tools for applying anti-skid chains, commonly known as "weed-chains," to the tires of motor vehicles, 15 the object of the invention being to provide an article of extreme simplicity wherein its members will have a pivotal movement with respect to each other to approach their chain-engaging jaws to draw the end links 20 of the chain toward each other up to and never beyond a spacing slightly less than the usual coupling member of the chain.

A further object of the invention is to provide a construction wherein the jaws may be adjusted so that their chain-engaging 25 hooked extremities will initially have different maximum spacings to suit the initial suppressions of the ends of each side chain member, the hooked ends having substantially 30 the same limit of mutual approachment in different positions of adjustment.

In the drawing:

Figure 1 is an elevational view of the device;

Fig. 2 is a plan view;

Fig. 3 is a vertical sectional view showing the manner in which the movable jaw is mounted; and

Fig. 4 is a detail of one of the chain engaging jaws.

The embodiment of the invention illustrated in the drawing includes a bar 1 which acts as a handle and which has on one end a tire tool 2 and on the other end a chain engaging jaw which includes a pair of spaced prongs 3. One edge of this bar 1 is provided with a series of depressions 4 which are substantially semi-circular in form. A movable jaw member 5 is mounted on the bar 1 slidably. This jaw member is provided at one end with a chain engaging jaw which includes a pair of spaced prongs 6 similar to the prongs 3 and is provided at the other end with a slot 7 through which 5 the bar 1 extends. The end of the slot remote from the prong 6 is closed by means of

a transversely extending integral bar 8 which is adapted to seat in any of the depressions 4 and the inner face of which is semi-circular so that the jaw member 5 may have a rocking movement when the bar is seated in one of the said depressions. The jaw on the end of the bar is of greater length than the thickness of the bar and the slot 7 in the jaw member 5 is equal substantially 65 in width to the thickness of the portion of the bar contiguous to the depressions 4 so that the jaw member is prevented from being displaced from the bar at the jaw end. The thickness of the bar increases away 70 from the jaw end until it is of greater thickness than the width of the slot so that the jaw member will be prevented from displacement from the end of the bar remote from the jaw end. 75

With this construction it will be noticed that the two ends of the chain may be gripped by the jaws and when so gripped the handle 1 may be actuated to draw the 80 ends together. Furthermore at this time the jaw member and the handle member will have free relative movement so that the ends of the chain may be readily pulled together.

In the operation of the device, the hook at the end of one of the jaws receives in its slot between its prongs, the narrow neck behind the endmost link at one end of the side member of the chain while the hook of the opposite jaw is engaged behind the usual coupling, the member 5 being slid along the 85 bar 1 and the cross bar or web 8 is engaged in the proper depression 4. The bar 1 is then swung in a direction away from the hooked end of the member 5 with the result that the side chain ends are drawn toward 90 each other until the wall of the slot 7 opposite to the web 8 strikes the bar 1, when the link at one end of the side chain will be found to overlie the notched edge of the coupling and may be pressed readily thereinto. 100 With reverse movement of the bar 1, the hooks may be disengaged. It will be noticed that the notches 4 are semi-circular notches so that the web 8 remains engaged whether the member 5 is in the position illustrated 105 with respect to the member 1 or whether it is swung to its opposite position as when engaged with the widely separated ends of a chain.

What we claim is:

A special tool for placing anti-skid chains on motor vehicle tires, consisting of a bar

having one end portion directed rearwardly with a compound curve, the chords of which are at an obtuse angle to the remainder of the bar and provided at its extremity with 5 fingers spaced apart to receive a chain link therebetween, the bar having arc-shaped notches in the rear face of its body portion, a second member having a passage at one end in which the bar is received for sliding 10 adjustments at times and having its opposite end portion directed away from the rearwardly directed end portion of the bar in the same plane and curved oppositely and similarly thereto and having spaced fingers 15 directed toward the first-named fingers and adapted to receive a link between them, the

outer wall of the passage having a rounded edge disposed to interchangeably engage the notches for pivotal movement of the second member to touch the inner wall of the passage against the bar at both sides of the second member at right angles to the bar, said inner wall of the passage being disposed to touch the bar with the finger ends in marked spaced relation. 20 25

In testimony whereof, we affix our signatures, in the presence of two witnesses.

JOHN C. MAXSON.

WILLIAM O. WALKER.
